SPEAKER ENCLOSURE

Aston L. Moore, 220 Hammond Place,
South Bend, Ind. 46601

Filed Oct. 13, 1967, Ser. No. 8,992

Term of patent 14 years

(Cl. D26—14)

FIG.1

I claim:

The ornamental design for a speaker enclosure, as shown and described.
